[57] ABSTRACT

In a missile, a small ramp structure is installed forward of each aerodynamic control fin to deflect and reduce air and particle flow away from the gap between the missile body and a control fin therefor.

RAMP FORWARD OF CONTROL FIN
BACKGROUND OF THE INVENTION

The invention relates to missile design.

Many missiles designed for attacking moving targets suffer extremely high pressures on, and heating of, the aerodynamic control fin shaft mechanisms during critical flight maneuvers. Impact of the air and airborne particles has caused the control fin shaft to erode and the result has been as drastic as the shearing off of the shaft and failure of the missile. Prior attempts to alleviate this problem have led to unacceptable increases in missile drag and weight.

PURPOSE OF THE INVENTION

A purpose of this invention is to provide a ramp forward of the control fin to shield the mounting shaft of the fin from flow of particles and air during missile flight to minimize erosion of the mounting shaft.

SUMMARY OF THE INVENTION

The invention comprises a shielding structure installed forwardly of a respective aerodynamic control fin for reducing the air and particle flow between the missile body and the control fin during flight of the missile. The invention reduces the shaft mechanism pressures and heating to acceptable levels while adding only minor weight and drag to the missile. The invention thus minimizes control fin failure during critical flight maneuvers without significantly reducing missile performance and maneuverability.

BRIEF DESCRIPTION OF THE DRAWINGS

FIG. 1 is a sectional view of the control fin area of a missile utilizing the invention.

FIG. 2 shows a missile utilizing the invention.

DESCRIPTION OF THE PREFERRED EMBODIMENT

Referring now to FIG. 1, an aerodynamic control fin 1 is secured to a rotatable shaft 2 extending from a missile body 3 for aerodynamic control of the missile. A shielding ramp 4 is installed on the missile body forwardly adjacent control fin 1 to deflect air and particle flow away from the gap 5 between missile body 3 and control fin 1. Ramp 4, preferably constructed of aluminum, is provided with an elevated aft end which projects laterally in front of the inner edge (leading edge) of fin 1. This laterally extending elevated end of the ramp is wide enough to cover the greatest deflections of fin 1 during critical flight maneuvers. Ramp 4 is coated with a non-particle producing ablative material 6, preferably teflon.

FIG. 2 shows a missile having a plurality of control fins 1 and respective ramp structures 4.

We claim:

1. In a missile including a body having a nose end and at least one aerodynamic control fin mounted on a rotatable shaft extending from said body, a shielding ramp attached to said body forwardly adjacent said fin for reducing air and particle flow between said body and said fin, said ramp being disposed with its elevated end laterally extending in front of the inner edge of said fin.
2. The apparatus in claim 1, wherein said shielding ramp has width equal to the greatest deflection of said fin during flight.
3. The apparatus in claim 2, wherein said shielding ramp is coated with a non-particle producing ablative material.
